VAPOR GENERATOR

Martin Frisch, New York, N. Y., assignor to Foster Wheeler Corporation, New York, N. Y., a corporation of New York

Application November 25, 1941, Serial No. 420,331

4 Claims. (Cl. 122—478)

This invention relates to vapor generators and more particularly pertains to apparatus for generating and superheating steam.

The invention provides a multiple furnace superheating steam generator of novel and compact arrangement with which superheat control at all loads on the generator is obtained.

The features and advantages which characterize the invention will be understood from the following description considered in connection with the accompanying drawing forming a part thereof, and in which:

Fig. 1 is a vertical sectional view of a steam generator embodying the invention, and

Fig. 2 is a horizontal sectional view taken on line 2—2 of Fig. 1.

Referring to the drawing, the steam generator illustrated has vertical refractory side walls 11 and 12, a rear wall 13, a front wall not shown, and roof portions 14 and 15. Adjacent the roof portion 15 is a steam and water drum 16, and between the roof portions 14 and 15 is a flue gas outlet 17. Within the setting are two spaced furnaces 18 and 19 which are disposed adjacent the side walls 11 and 12 respectively. The inner boundary of the furnace 18 is defined by a vertical baffle wall 20 which extends upwardly from the lower portion of the setting and terminates short of the roof to provide a gas outlet 21 in the upper portion of the furnace. The inner boundary of the furnace 19 is similarly defined by a vertical baffle wall 22 which terminates short of the roof to provide a gas outlet 23 in the upper portion of the furnace. A stoker 24 to which fuel is supplied from a hopper 25 fires the furnace 18, and a stoker 26 to which fuel is supplied from a hopper 27 and operated independently of the stoker 26, fires the furnace 19. The stokers 24 and 26 discharge into suitable ash pits 28 and 29 respectively. Extending between the upper drum 16 and a lower drum 30, parallel to the upper drum, is a vertical bank of steam generating tubes 31 which are swept by the gases flowing from the furnace 19 to the flue gas outlet 17 through vertical, substantially parallel gas passages 32 and 33 which are connected in series. Passage 32 is formed between baffle 22 and a baffle 34 which extends downwardly from drum 16 to a point short of the drum 30, and communicates with the furnace 19 through gas outlet 23 and with the passage 33 at its lower end. Passage 33 is formed between baffle 34 and a baffle 35 at the opposite side of the tube bank 31 which extends upwardly from drum 30 and terminates short of the drum 16.

The inner surface of the side wall 11 is lined with vertical water wall tubes 36 which extend across the upper end of the setting and are connected at their upper ends to the drum 16, the lower ends being connected to header 37 which is supplied with circulating water by suitable external downcomer connections, not shown. The inner surface of the side wall 12 is similarly lined with vertical water wall tubes 39 which are connected at their upper ends to the drum 16, and at their lower ends to header 40 which is connected into the boiler circulation. The furnace side of the baffle wall 22 is lined by vertical water wall tubes 42 which extend to the drum 16 from lower header 43 which is connected into the boiler circulation. Adjacent the gas outlet 23 the tubes 42 are spread apart to provide a passage for the gases. It will be understood that the inner surfaces of the front and rear walls are lined with water wall tubes, not shown, which are connected into the boiler circulation.

In the form shown, a combination radiant and convection superheater is utilized and is so arranged and disposed that it is subject to the heat 23 of the gases produced in one furnace only. In the superheater furnace 18, the furnace side of the baffle wall 20 is lined with vertical radiant heat superheater tubes 47 and 48, which are alternately disposed, and tangent to each other and form a continuous panel or section of radiant heat absorbing surface except at the furnace gas outlet passage 21 where the tubes are spread apart and bent outwardly from the furnace as shown in Fig. 2. The tubes 47 and 48 which are connected to the steam space of the drum 16 in two spaced longitudinal rows, conduct steam downwardly in one pass to a lower header 49 from which the steam flows upwardly in one pass through the tubes 48 to a point adjacent the top 40 of a baffle wall 50 which extends downwardly from the roof 14 of the setting in spaced relationship to the baffle 20 to a point above the drum 30 to form a gas passage 51 which is in communication at its upper end with furnace 18 through passage 21. Adjacent the top of the baffle wall 50, the tubes 48 of the superheater pass through the baffle 50 and are formed into a plurality of return bend loops of a convection superheater section 52, which is vertically disposed in the space between the baffles 50 and 35 forming a gas passage for the gases flowing from the furnace 18 and through the passage 51 to the flue gas outlet 17. As shown, the tubes 48 of the radiant heat superheater section and the tubes of the convection section 52, which are arranged for series flow

of steam therethrough, are continuous with each other, and no intermediate header connections are required. The elements of the convection superheater section 52 are connected to a superheater outlet header 53 which is fixed in position below the drum 30 and from which the superheated steam is conducted to the point of use.

In operation, the gases produced in the saturated steam furnace 19 flow upwardly through the furnace and out thereof through the outlet, downwardly through passage 32 and upwardly through passage 33 over the steam generating tubes 31 to the outlet 17. Saturated steam is conducted from the upper drum 16 and flows downwardly through superheater tubes 47 and upwardly through tubes 48, mainly in radiant heat exchange relationship with the gases produced in the superheater furnace 18. From the radiant section of the superheater, the steam flows through the convection section 52 in convection heat exchange relationship with the gases flowing from the furnace 18 through outlet 21, downwardly through passage 51 and upwardly over the convection section 52 and out the outlet 17. The quantity of steam produced will be determined largely by the rate at which the furnace 19 is fired, although some steam will be generated in the water walls of the furnace 18. Inasmuch as the gases produced in the saturated steam furnace 19 do not flow in heat exchange relationship with the superheater, the degree to which the steam is superheated will be determined by the degree to which the superheater furnace 18 is fired. Furnace 18 may be fired to obtain the superheat temperature desired at any load on the generator, or it may be fired to obtain and to maintain a substantially constant degree of superheat at all loads on the generator. The superheating characteristics of the combination radiant heat and convection superheater employed, contribute to the maintenance of a constant superheat temperature.

With this arrangement, it will be observed that the steam flow in the convection section of the superheater is from the side near the wall 50 to the side near the steam generating section. Thus the superheater elements at the highest steam temperature are not subjected to the highest temperature gases flowing from the furnace 18 through outlet 21.

Since the superheater sections are shielded from the gases leaving one of the furnaces, the steam generator may be started up by firing that furnace only, thus eliminating any necessity for flooding the superheater during starting up periods. This considerably shortens the time ordinarily required to bring the unit onto the line. Also, if a feed water heater were out of service, a constant steam temperature can be maintained without the use of a by-pass or any other means of superheat control except for the differential firing provided.

The elimination of intermediate header connections between the radiant and convection sections of the superheater simplifies and reduces the cost of construction of the superheater and reduces the pressure drop, although intermediate headers may be employed, if desired.

It will be understood that changes may be made in the form, location and relative arrangement of the several parts of the steam generator disclosed without departing from the principles of the invention. Consequently, the invention is

not to be limited excepting by the scope of the appended claims.

What is claimed is:

1. Vapor generating apparatus comprising a setting, spaced furnaces in the setting, means in the lower portion of each furnace for firing the furnace, each furnace having a gas outlet opening at its upper portion in communication with the space between the furnaces, the setting having a gas outlet at its upper portion communicating with said space, means forming a plurality of vertical, substantially parallel gas passages in said space connected in series and communicating with the gas outlet opening of one furnace and the gas outlet of the setting, vapor generating surface in the gas passage discharging directly into said gas outlet, means forming a plurality of other gas passages in said space communicating with the gas outlet opening of another furnace and the gas outlet of the setting, said other passages being vertical and substantially parallel and connected in series, and a superheater having a part disposed in the other gas passage discharging directly into said gas outlet.
2. Vapor generating apparatus comprising a setting, spaced furnaces in the setting, means in the lower portion of each furnace for firing the furnace, each furnace having a gas outlet opening at its upper portion in communication with the space between the furnaces, the setting having a gas outlet at its upper portion communicating with said space, means forming a plurality of vertical, substantially parallel gas passages in said space connected in series and communicating with the gas outlet opening of one furnace and the gas outlet of the setting, vapor generating surface in the gas passage discharging directly into said gas outlet, means forming a plurality of other gas passages in said space communicating with the gas outlet opening of another furnace and the gas outlet of the setting, said other passages being vertical and substantially parallel and connected in series, and a superheater having a part disposed in the other gas passage discharging directly into said gas outlet.
3. Vapor generating apparatus comprising a setting, spaced furnaces in the setting, means in the lower portion of each furnace for firing the furnace, each furnace having a gas outlet opening at its upper portion in communication with the space between the furnaces, the setting having a gas outlet at its upper portion communicating with said space, means forming two vertical, substantially parallel gas passages in said space connected at their lower end, the first passage communicating with the gas outlet opening of one furnace for flow of gases downwardly therein, the second passage communicating with the gas outlet of the setting for flow of the gases upwardly therein, vapor generating surface in the second gas passage, means forming two other vertical, substantially parallel gas passages in said space connected at their lower end, the first of the other passages communicating with the gas outlet opening of another furnace for the flow of gases downwardly therein, the second of the other passages communicating with the gas outlet of the setting for flow of gases upwardly therein, and a superheater having a part thereof disposed adjacent a wall of said other furnace and another part disposed in the second of the other gas passages.
4. Vapor generating apparatus comprising a

setting, spaced furnaces in the setting, a stoker for firing each furnace, each furnace having a gas outlet opening at its upper portion in communication with the space between the furnaces, the setting having a gas outlet at its upper portion communicating with said space, means forming two vertical, substantially parallel gas passages in said space connected at their lower end, the first passage communicating with the gas outlet opening of one furnace for flow of gases downwardly therein, the second passage communicating with the gas outlet of the setting for flow of the gases upwardly therein, vapor gener-

ating surface in the second gas passage, means forming two other vertical, substantially parallel gas passages in said space connected at their lower end, the first of the other passages communicating with the gas outlet opening of another furnace for the flow of gases downwardly therein, the second of the other passages communicating with the gas outlet of the setting for flow of gases upwardly therein, and a superheater having a part thereof disposed adjacent a wall of said other furnace and another part disposed in the second of the other gas passages.
